UNITED STATES PATENT OFFICE.

WILLIAM DIETER, OF NEWARK, NEW JERSEY, ASSIGNOR TO VITTEA DEVELOPMENT CORPORATION, A CORPORATION OF DELAWARE.

TORPEDO DEPTH GEAR.

Application filed December 31, 1921. Serial No. 526,332.

To all whom it may concern:

Be it known that I, WILLIAM DIETER, a citizen of the United States of America, residing in Newark, in the county of Essex 5 and State of New Jersey, have invented certain new and useful Improvements in Torpedo Depth Gears, of which the following is a specification.

This invention relates to means for controlling the movements of the pendulum forming an element of the depth or immersion mechanism of an automobile torpedo.

As is well understood, the depth mechanism of a torpedo is controlled both by a hydrostat and a pendulum; the function of the hydrostat being to determine the set depth which the torpedo shall tend to follow, and the function of the pendulum being to keep the torpedo level and check any attempt to rise or dive. Both of these elements are connected to the valve of the depth engine, so that the latter, and the rudders which it operates, respond to a movement of either the hydrostat diaphragm or the pendulum, or to a resultant of their combined movements when both move. The result is that in actual practice the torpedo, after reaching its prescribed depth (as determined by the adjustment of the hydrostat), tends to travel at that depth, following a sinuous course in a succession of vertical undulations. But in launching, and again when slowing down at the end of the run, the rapid acceleration or retardation of the torpedo causes the pendulum to swing violently backward or forward (relatively), which movements are followed by forcible return or reactive movements, and these abnormal movements of the pendulum cause extreme up or down depth rudder movements which in turn cause the torpedo to suddenly dive or rise, often with serious results. The aim of the present invention is to prevent or greatly reduce these 45 disadvantageous perturbations and cause the pendulum to quickly recover from any serious shock and settle down to normal action.

The accompanying drawing illustrates the preferred embodiment of the invention.

Figure 1 is a side elevation of a torpedo, its hull being partly broken away to show the depth mechanism in elevation.

Fig. 2 is a fragmentary vertical section of the lower portion of the pendulum on a larger scale, the plane of the section be-

ing in the longitudinal mid-plane of the torpedo.

Fig. 3 is a fragmentary section corresponding to Fig. 2 and showing a further development of the invention. 60

The general construction shown as the basis for the application of the present invention is substantially similar to that illustrated in the patent to Leavitt, No. 1,080,116, dated December 2, 1913. Or the 65 construction shown in my Patent No. 1,190,871, July 11, 1916, may be used.

A is the torpedo hull, B the hydrostat, C the pendulum, D the depth engine, and E the gyroscope casing. Of the hydrostat, 70 only the exterior is shown, namely, the base *a* and spring casing *b*, between which parts the internal diaphragm is commonly secured. From the diaphragm the movement is communicated through a lever which may 75 be in the form of an elbow lever *c* (see said Patent No. 1,080,116), one arm *c'* of which is shown in full lines. The pendulum is connected by a rod *d* to one arm of a floating lever *f* the fulcrum of which is carried 80 on the lever arm *c'*, and the opposite arm of which engages a valve rod *g* of the depth engine D. The pendulum is mounted to swing in the longitudinal plane, and is provided with light springs *h h* which act to 85 press it toward its mid-position, and with spring buffers *i i*, which, as the pendulum swings, strike opposite stops *j j'* to cushion and limit the movement of the pendulum. 90 All of the parts thus far described are common in the existing Bliss-Leavitt torpedo.

The present invention introduces an additional cushioning means for checking the swinging movements of the pendulum, and which act in advance of the buffers *i i*. The 95 added means consist essentially of springs or spring-pressed parts acting to limit the swing of the pendulum, and coming into action in advance of the buffers, and acting with less resistance than is afforded by the buffers. 100 It results that in addition to gravity the pendulum is acted upon by three forces, namely, that of the light springs *h h* which constantly tend to bring the pendulum to mid-position; that of the cushioning means 105 provided by the present invention, which act only upon the swing of the pendulum in either direction, and come into action to check that swing in advance of the action of the buffers; and, finally, as the swing 110

becomes greater, that of the buffers which come into action and oppose a heavier stress for checking the swing of the pendulum.

While the cushioning devices provided by the present invention may be variously constructed, the embodiment shown in Fig. 2 is considered preferable because of its compactness and convenience. The buffers *i*, *i*, which, as heretofore, are formed as plungers 10 capable of sliding endwise in suitable bearings, and both pressed outward against stop shoulders by the action of a single heavy spring *k* between them, are modified by being made tubular, so that each buffer affords 15 a sliding bearing within it for a pin or plunger *F*. Each pin *F* has a head *F'* which seats against a shoulder formed by the inner end of the buffer *i*, and when thus seated the outer end of the pin *F* projects 20 beyond the end of the buffer *i* for a distance which is more or less variable, but is approximately half the space between the buffer and abutment or stop when the pendulum is at mid-swing, as shown in Fig. 2. Between the heads *F'* of the two pins is introduced 25 a spring *G* which is of considerably lighter stress than the spring *k*. The described construction is simple, compact, and convenient, and has the advantage of centering 30 the axes of the buffers and cushioning pins or plungers, so that all the forces act in a direct line. To facilitate the assembling of the parts, the outer stop shoulder in one of the housings *m* for the buffers 35 *i* is made detachable, being formed as a screw plug *n*.

In operation, as the pendulum swings forward or aft, one of the cushioning pins *F* first strikes the abutment *j* or *j'*, and the further swing of the pendulum pushes in this pin against the stress of spring *G*, which reacts against the head *F'* of the other cushioning pin while the latter is firmly seated. Thus the swing of the pendulum is opposed 45 to the extent of the stress of the spring *G*. If the pendulum swings enough farther to bring the buffer *i* against the abutment, its further swing is thereupon opposed by the larger stress of the spring *k* as the buffer 50 *i* is pressed back relatively to the pendulum. When the pendulum is stopped at the end of its swing, the stress of one or other of these springs, as the case may be, is exerted to start the backward swing of the pendulum, 55 toward its mid-position; and if this swing throws over to the other side, the same operations are repeated with respect to the pin *F* and buffer *i* on the opposite side.

The present invention has the practical 60 advantage of overcoming serious defects in the operation of torpedoes. With any torpedo, at the instant of launching the forward movement imparted to the torpedo causes the pendulum to lag behind, or swing 65 relatively backward, and as the acceleration

in launching is extremely rapid, this has the effect of a shock which throws the pendulum violently backward relatively to the torpedo; this is followed by a reactive forward swing of the pendulum, and several 70 diminishing contrary vibrations ensue before the pendulum settles down to its substantially mid-position. The first backward swing throws the depth rudder down, and causes the torpedo to dive deeply; the reaction therefrom causes it to rise abruptly and sometimes to broach; this is followed by another dive, and this by another rise, these effects diminishing until the torpedo reaches substantial equilibrium at its normal depth. 75 Conversely, when the propulsion is stopped at the end of the run the torpedo suddenly slows down (falling in a few seconds from say 30 knots to about 4 knots), which causes the pendulum to swing forward, followed by a backward reaction, and reversing the effects at launching; and these movements of the pendulum cause the torpedo to first rise, or broach and then dive deeply, followed by diminishing undulations. Either 80 of the deep dives thus experienced may result in the torpedo burying its bow in the bottom of the waterway if the water is shallow.

These extreme perturbations are in great 95 part prevented by the present invention. An extreme swing of the pendulum first brings the cushioning pin *F* against the abutment, and its further movement is opposed by the spring *G*, which slows down the pendulum 100 before the buffer *i* strikes the abutment, so that there is a reduced buffer action and reduced reaction; consequently the return swing of the pendulum starts with much less energy, and in turn is checked by the contrary, action of the opposite cushioning means *F* *G*, so that the pendulum is quickly 105 slowed down and brought within its normal limits of movement in normal running, that is, to such reduced oscillations as correspond 110 to the free movement between the contacting positions of the pins *F* *F*.

As a further development of the invention, the cushioning effect, instead of being confined to one cushioning pin *F* at each end, 115 and one spring *G*, may be divided between two or more pins and springs, the pins having different degrees of projection, and the springs having different stresses. As an example, there is shown in Fig. 3 a construction 120 in which the cushioning pin *F* of Fig. 2 is substituted by a tubular pin *F'* and a central pin *F*², the latter projecting beyond the former, and these respective pins receiving the stress of springs *G*¹ and *G*², the latter 125 having the minimum stress and the former a stress intermediate between such stress and that of the buffer spring *k*. The operation is the same as before described, except that upon the first encounter of the spring *F*² 130

with the abutment j , a diminished cushioning effect is accomplished, followed, as the pendulum swings farther, by the abutting of the pin F^1 against the abutment, and the 5 added resistance of the spring G^1 to the continued swing of the pendulum. The proportions may be such that the free swing of the pendulum before the pins F^2 touch the abutments is the same as in Fig. 2; or the pins F^2 10 may be caused to project farther, so as to limit the free swing of the pendulum within a smaller angle and thereby cause the pins F^2 and spring G^2 to act sooner than with the proportions given in Fig. 2. The proportions 15 may be such that the effect of the minor cushioning means will be to tend to diminish the sinuosities in the path normally traversed by the torpedo when running at its set depth; that is to say, to diminish the vertical undulations of such sinuous course.

It will be understood that while the concentric arrangement of pins and buffers, and of the minor and major springs shown in the examples herein illustrated, is deemed 25 preferable for convenience in construction, and for compactness, yet this arrangement may be departed from, it being within the invention to apply cushioning springs according to any arrangement and construction 30 which will accomplish the operations herein set forth.

What I claim is:—

1. In a torpedo, in combination with its pendulum and stops, of spring cushioning 35 means of graduated stress mounted to come into action at successive points in the swing

of the pendulum, to afford resistance to the swing of the pendulum varying with the amplitude of such swing.

2. In a torpedo, in combination with its 40 pendulum and stops, and with the normal spring buffers for checking its extreme swing, of cushioning means effective on a swing of less amplitude, and opposing a 45 smaller stress to the swing of the pendulum.

3. In a torpedo, in combination with its pendulum and stops, of a heavy buffer and lighter cushioning spring, the former effective toward the end of the swing, and the 50 latter upon a smaller swing, of the pendulum.

4. In a torpedo, in combination with its pendulum and stops, of buffers projecting beyond the pendulum to abut the stops in 55 advance of the extreme movement of the pendulum, and cushioning pins projecting further to abut the stops in advance of the abutment of the buffers, with a relatively stiff spring for the buffers and a lighter 60 spring for the cushioning pins.

5. In a torpedo, in combination with its pendulum and stops, of tubular buffers projecting beyond the pendulum, and cushioning pins projecting through and beyond the 65 buffers, a heavy outer spring for the buffers, and a lighter inner spring for the cushioning pins.

In witness whereof, I have hereunto signed my name.

WILLIAM DIETER.
